SHOE FORM

Daniel Newhouse, New York, N. Y.

Application December 5, 1947, Serial No. 789,930

3 Claims. (Cl. 12—128)

1

My invention relates to a new and improved hollow and bendable and resilient shoe-form, which is used as a mount for shoes in display windows and the like.

According to my invention, I make said shoe-form of two separately molded one-piece body-members, which can be made of any suitable resilient plastic of the thermoplastic or thermo-setting type, or of any other moldable material. These one-piece body-members are respectively designated as a pin body-member and a socket body-member.

Each said one-piece body-member can be made by injection molding or in any other manner. Said body-members are preferably made of the same material, such as cellulose acetate. Each said body-member has an internal concave or recessed face, so that each said body-member has a rear upstanding flange, a top flange, and a bottom flange. The rear upstanding flange may have an external concave face. The top end of said upstanding flange is continuous with a rear portion of the top flange. Said rear portion of the top flange may be planar and horizontal. At its front end, said rear portion of the top flange is continuous with a downwardly inclined front portion of said top flange, which extends to the front of the form.

The bottom flanges of the assembled body-members are shaped so that their edges are spaced from each other, save at the heel and toe of the form, at which the edges of said bottom flanges abut to form a suitable joint, as exemplified by a lap-joint. The edges of said rear and top flanges also abut each other to form a suitable joint, as exemplified by a lap-joint.

Each said body-member can be molded, as by injection molding, from the same thermoplastic material, as exemplified by cellulose acetate.

It is well-known to bond bodies made of thermo-plastic material to each other by using a suitable cement, or by softening the edge-portions of said bodies and pressing said softened edge-portions against each other. Such bonding methods are described at pp. 608—609, 615 of "Handbook of Plastics" by Simonds and Ellis, published in 1943 by D. Van Nostrand Company Inc.

It is very difficult, if not possible, to hold two such resilient body-members in proper assembled relation by means of a lap-joint while bonding them, or to provide a secure union between such resilient body-members by merely bonding them at the edges thereof which form the joint.

According to my invention, I provide the pin

2

body-member with a plurality of integral and imperforate pin-lugs, each of which has a planar end-face from which an integral reduced assembly pin extends laterally beyond the edges of the flanges of said pin-body member. Said planar end-faces of said pin-lugs are flush with the inner lip which forms the inner element of the lap-joint. I provide the socket body-member with a plurality of integral socket-lugs, which have respective recesses in which the respective assembly pins fit accurately when said body-members are assembled. Said socket-lugs have planar end-faces, which abut the planar end-faces of the pin-lugs, when said body-members are assembled. When thus assembled, the end-faces of said assembly pins are spaced laterally from the inner end-wall of the recesses of said socket-lugs. This combination ensures an easy and accurate assembly of the body-members. Said assembled body-members are bonded to each other, either by using a cement or a softening agent, at the elements of the lap-joint. Optionally, said body-members may be thus bonded to each other at the abutting faces of the pin-lugs and socket-lugs, and also optionally at the assembly-pins and the internal walls of the recesses of the socket-lugs.

Other objects and advantages of my invention are stated in the annexed description and drawings which illustrate a preferred embodiment thereof.

Fig. 1 is a side elevation of the assembled form;

Fig. 2 is a bottom plan view of the assembled form, partially in horizontal cross-section;

Fig. 3 is an internal elevation on the line 3—3 of Fig. 2, showing the pin body-member;

Fig. 4 is a section of the assembled body-members, taken along the line 4—4 of Fig. 3; and

Fig. 5 is a section of the assembled body-members taken along the line 5—5 of Fig. 3.

The drawings are substantially to scale of a commercial embodiment, and reference is made to such scale as part of the disclosure to disclose the shapes and relative sizes of the parts.

The pin body-member 2 has a lip 8, which forms the inner element of the preferred lap-joint, as illustrated in Fig. 5. This lip 8 is interrupted between the horizontally disposed points 6 and 7, which define the ends of the bottom flange of pin body-member 2.

Directly adjacent to and directly inwardly of lip 8, the pin body-member 2 has a plurality of integral pin-lugs 3, each of which has a planar end-face, as shown in Fig. 2. Each pin-lug 3 has

an integral assembly-pin 4, of cylindrical shape, which projects laterally beyond the respective end-face.

The socket body-member 1 has a plurality of integral socket-lugs 5, each of which has a recessed planar end-face. Said socket-lugs 5 are directly adjacent to the inner faces of the flanges of socket body-member 1.

When the body-members 1 and 2 are assembled, the planar end-faces of the pin-lugs 3 and socket-lugs 5 abut each other, and each assembly pin 4 fits closely in a recess of a respective socket-lug 5, with the end-face of each assembly pin 4 spaced laterally from the end-face of the respective recess.

The socket body-member 1 has a lip 9 which forms a lap-joint with the lip 8 of the pin body-member 1. A lap-joint is thus provided at the edges of the flanges of said body-members, save between the points 6 and 7, between which the edges of the bottom flanges are spaced from each other, so that the assembled and bonded body-members 1 and 2 are easily laterally bendable between the points 6 and 7. This facilitates the application and removal of the shoes from the finished shoe-form and the proper display of the shoes.

By means of injection molding, I can easily form a plurality of pin body-members 2 and socket body-members 1 in a single injection step.

Other plastics and moldable materials which I can use are disclosed in said "Handbook of Plastics."

The finished form is sufficiently bendable, so that parts of the separated edges of the bottom flanges can be contacted under lateral pressure. Under this severe test, the bond between the body-members remains unimpaired, which could not be done if said body-members were only bonded at the lap-joint 8-9, without providing the pin-lugs and the socket-lugs. The planar faces of said pin-lugs and socket-lugs abut each other, when the lips 8 and 9 are in final registration to form the lap-joint, so that said pin-lugs and socket-lugs provide supplemental registration means.

I have disclosed a preferred embodiment of my invention, but numerous changes and omissions and additions can be made without departing from its scope.

I claim:

1. A resilient shoe form comprising two resilient body members, said body members being concave and complementary, said body members being joined to form a joint along the front, top and back of said shoe form, pins providing a rigid connection between said body members adjacent to said joint, said body members being bonded together along said joint, said shoe form being open at the bottom to allow inward compression of the sides of said shoe form.

2. A resilient shoe form comprising a one-piece resilient pin body-member and a one-piece resilient socket body-member, said resilient body-members having internal concave faces to provide flanges at which said body-members abut each other to form a joint, said joint extending along the rear of the bottom of said shoe-form, along all top portions of said shoe-form and along the front of the bottom of said shoe-form, the remainder of said bottom of said shoe-form being open, pin-lugs integral with the inner faces of said flanges of said pin body-member and adjacent to said joint, socket-lugs integral with the inner faces of said flanges of said socket body-member and adjacent to said joint, said pin-lugs having end-faces from which assembly pins extend laterally, said socket-lugs having end-faces from which socket-recesses extend laterally inwardly, said end-faces of said pin-lugs abutting said end-faces of said socket-lugs when said flanges abut each other to form said joint, said assembly pins being located in said recesses.

3. A resilient shoe form comprising complementary resilient first and second body-members having internal concave faces to provide flanges at which said body-members abut each other to form a joint, said joint extending along the rear of the bottom of said shoe-form, along all top portions of said shoe-form and along the front of the bottom of said shoe-form, the remainder of said bottom of said shoe-form being open, a first set of lugs respectively connected to said first body member adjacent said joint, a second set of lugs respectively connected to said second body member adjacent said joint, the lugs of said second set being respectively in abutment with and complementary to the respective lugs of said first set, means for fastening said body members together at said joint, means for fastening the lugs of said first and second sets of lugs together at the respective junctions therebetween.
